ASH TRAY

Felix Alexander Joseph, Scarsdale, N. Y.; now by
judicial change of name Felix Joseph Alex-
ander

Application August 26, 1941, Serial No. 408,341

5 Claims. (Cl. 131—235)

The present invention relates to a combination ash tray and cigarette snuffing or extinguishing device. This application is a continuation-in-part of applicant's co-pending application, Serial No. 390,459, filed April 26, 1941, and issued September 1, 1942 as Patent No. 2,294,618.

An ash tray is ordinarily provided with an ash receptacle to receive ashes from burned cigarettes and also with a ledge or rest often in the form of a shallow groove where a lighted cigarette 10 may be laid temporarily with its lighted end overhanging the ash receptacle and its other end projecting outwardly beyond the supporting surface. If a cigarette is allowed to remain on this temporary support unattended, the lighted end slowly burns away until it reaches a point where it is lighter than the projecting unlighted end of the cigarette, whereupon the cigarette is overbalanced and tips off the support, falling onto the floor or furniture where it is liable to start 20 a fire or to burn and damage the surface on which it falls. It is an object of the present invention to overcome this danger by providing an ash tray having a support where a cigarette may be placed and allowed to continue burning temporarily and 25 a snuffing or extinguishing device which will extinguish the cigarette before it burns a sufficient distance to overbalance and tip off of the support. A further object of the invention is to provide an ash tray with an effective snuffing or 30 extinguishing device without interfering with the ease with which a partially burned cigarette can be picked up from the temporary support even when only a short unsmoked end of the cigarette remains, and to provide an ash tray which is 35 neat in appearance, easily cleaned and free of lateral projections of small cross section which are liable to be broken off.

The nature and advantages of the invention will be fully understood from the following description of the embodiment shown by way of example in the accompanying drawing, in which

Fig. 1 is a perspective view of an ash tray embodying the invention.

Fig. 2 is a top plan view of the ash tray shown in Fig. 1.

Fig. 3 is a sectional view taken on the line 3—3 in Fig. 2.

Fig. 4 is a sectional view taken on the line 4—4 in Fig. 2.

Fig. 5 is an enlarged fragmentary sectional view taken on the line 5—5 in Fig. 2.

The ash tray shown by way of example in the drawing is formed with a bottom 11, sides 12, and a substantially flat top surface 13. Extend-

ing downwardly from the top surface is a well 14, which forms a receptacle for cigarette butts and the ashes of burned cigarettes. It will be seen that the flat top surface of the ash tray forms a support or rest on which a burning cigarette may be temporarily placed with its burning end overhanging the ash receptacle. The flat topped surface not only facilitates molding when the ash tray is made of a moldable material such as glass and provides an attractive reflecting surface, but also facilitates picking up a burning cigarette lying on the supporting surface. With a cigarette supported on a flat surface, the tips of the thumb and fingers may be inserted under the cigarette, whereby it may easily be picked up while if the cigarette were lying in a groove even though the groove be relatively flat or shallow, the thumb and finger tips cannot be slipped under the cigarette to lift it from the support. With the cigarette lying in a groove having a depth equal to one-half the diameter of the cigarette, or more, it is quite impossible to grip the portion of the cigarette disposed in the groove. With a shallower groove the cigarette may be picked up with difficulty by pinching or gripping it tightly though there is danger of breaking the cigarette paper. With the flat supporting surface in accordance with the present invention on the other hand, the cigarette may be picked up with extreme ease, even though it is so short that it does not project beyond the edge of the supporting surface.

While it is desirable to provide an ash tray with a support on which a lighted cigarette may be placed temporarily, it is undesirable for the cigarette to continue to burn indefinitely. If the cigarette is balanced on the support with the lighted end overhanging the ash receptacle and the other end projecting outwardly beyond the edge of the support, the cigarette will become unbalanced when the lighted end has burned back a certain distance and will topple off the support, burning the furniture or floor onto which it falls and creating a serious fire hazard. Moreover the smoldering cigarette gives off smoke and fumes which may become objectionable and it is therefore desirable to extinguish the cigarette if left unattended on the support for a protracted period of time. To overcome these serious objections, there is provided in combination with the flat supporting surface a cigarette snuffing or extinguishing device interposed between the flat surface and the ash receptacle so that if a cigarette burns back beyond the edge of the ash receptacle, it will be put out. As shown in

the drawing, the extinguishing device consists in a groove 15, formed between spaced projections or lugs 16, extending upwardly from the flat top surface of the ash tray. The projections 16 are located adjacent an edge of the well 14 so that the groove 15 opens at one end 15a over the ash receptacle and opens at the other end 15b onto the flat surface 13. The bottom of the groove is preferably curved to conform approximately to the curvature of a cigarette and its lowermost portion is in substantially the same plane as the flat supporting surface 13 so that a cigarette lying on said surface will also lie on the bottom of the groove. The groove is made slightly wider than the diameter of a cigarette so that the walls of the groove will conform closely to the surface of a cigarette without gripping or binding the cigarette in any way. The depth of the groove should be not substantially less than half the diameter of a cigarette, and is preferably slightly greater, although it is unnecessary and undesirable for the grooves to be deeper than the diameter of a cigarette, as this requires the projection 16 to be unnecessarily high. For example, with ash trays intended for standard size cigarettes which are approximately $\frac{1}{2}$ of an inch in diameter, the groove may be $\frac{1}{4}$ of an inch wide and $\frac{1}{8}$ of an inch deep. The relation between the walls of the groove and the surface of a cigarette is shown in the enlarged cross-sectional view of Fig. 5.

The ability of the groove 15 to extinguish a lighted cigarette derives from a number of factors. The combustion of the tobacco in a cigarette is ordinarily not self-sustaining. The paper wrapper is more combustible, and the heat generated by the burning paper helps keep the tobacco at a temperature above its ignition point. It is hence of primary importance to extinguish the cigarette paper, particularly that portion of the paper at the bottom side of the cigarette, as the combustion of this portion of the paper being below the tobacco, is more effective in keeping the tobacco alight than paper at the sides of or above the tobacco. With the extinguishing device of the present invention, the paper below the tobacco is extinguished by reason of the close contact of the walls of the groove with the bottom half of the cigarette, thereby conducting heat away from the burning end of the cigarette, shutting off oxygen from the paper and tobacco and collecting a pocket of carbon dioxide which will not support combustion. Moreover, the moisture resulting from the burning cigarette collects on the relatively cooler surfaces of the grooves, and where these surfaces contact or lie close to the paper, this moisture dampens the paper and further quenches its combustion. The amount of moisture collected is not enough to run down to the bottom of the groove, and hence moistening of the paper occurs only at the points where there is substantially close contact between the cigarette and the walls of the grooves. It is important for the grooves to fit closely the surface of the cigarette, and yet be sufficiently wide so that the sides of the grooves do not grip or bind the cigarette so as to hold it up off the bottom of the groove, leaving an air space for a supply of oxygen below the cigarette and preventing the dampening and quenching of the portions of paper beneath the tobacco.

The groove 15 should be of sufficient length to insure extinguishing a cigarette even in a draft, a length of approximately $\frac{1}{8}$ the length of a cigarette being ordinarily sufficient for this pur-

pose. Taking the standard length of a cigarette as $2\frac{3}{4}$ to $3\frac{1}{4}$ inches, this means that the grooves should be at least approximately $\frac{1}{4}$ inch long. On the other hand, the grooves should not be long enough to interfere with readily picking a cigarette up from the flat supporting surface 13. The flat surface or ledge for supporting the cigarette should extend beyond the end of the groove a distance of from $\frac{1}{2}$ to $1\frac{1}{2}$ times the length of the groove and preferably not substantially less than the length of the groove. By restricting the length of the groove and providing a flat supporting surface of substantial extent in line with the groove to support the cigarette, a partially burned cigarette, even though barely long enough to be smoked, will always extend beyond the end of the groove on to the flat supporting surface where it can easily be picked up by slipping the finger and thumb tips under it. The extinguishing device prevents the cigarette from rolling and hence facilitates slipping the tip of the thumb and fingers under it to pick it up from the support without rolling it off of the flat surface. However, a preferred characteristic of the extinguishing device shown in the drawing, is that it in no way grips or binds the cigarette and therefore does not interfere with picking it up from the flat supporting surface 13.

The combined length of the groove and the distance the flat top surface or ledge extends in line with the grooves should be not less than approximately $\frac{1}{2}$ the length of a cigarette in order that a freshly lighted cigarette placed on the support will be extinguished before unbalancing and tipping off. As a cigarette is normally placed with its lighted end projecting at least a short distance over the ash receptacle 14, the combined length of the groove and supporting surface may be slightly less for example, $\frac{3}{4}$ the length of a cigarette, but a lower limit of $\frac{1}{2}$ the length of a cigarette is preferable. As pointed out above, the length of the projections 16 forming the groove 15 is limited to avoid interfering with picking up the lighted cigarette. The flat top surface 13 may be extended farther than the minimum necessary to provide an adequate flat supporting surface for the cigarette, but it is generally desirable to restrict the over-all dimensions of the ash tray to prevent its becoming too large and bulky. In the embodiment shown, the grooves and the flat supporting surface extending in line with the grooves are of approximately equal length, each being substantially $\frac{1}{4}$ the length of a cigarette, so that the combined length is about $\frac{1}{2}$ the length of a cigarette.

While the ash tray of the present invention may be made of any material, it particularly lends itself to molding and is hence preferably made of glass or other moldable material. It will be appreciated that the novel combination of a flat supporting surface and a cigarette extinguishing device may be embodied in a cigarette support for use with an ash receptacle of any desired type with which it may be permanently or detachably united or quite apart from any ash receptacle, for example, as a cigarette support and extinguishing means for outdoor use or elsewhere where ashes are not objectionable. The ash tray shown in the drawing and described above is intended merely as an example and the novel combination of the invention may be incorporated in various forms as desired.

Having thus described my invention, what I

claim as new and desire to secure by Letters Patent is:

1. In an ash tray the combination of a substantially flat cigarette supporting surface, a well forming an ash receptacle, and extinguishing means comprising stationary spaced projections extending upward from said flat surface adjacent an edge of said well and forming between them a groove having a width slightly greater than the diameter of a cigarette and a depth of from one-half to one diameter of a cigarette, the bottom of said groove conforming approximately to the curved surface of a cigarette and having its lowermost portion in substantially the plane of said flat surface of the ash tray and forming a continuation of said surface.

2. In an ash tray, the combination of a substantially flat top surface, a well forming an ash receptacle, and extinguishing means comprising spaced upwardly projecting portions located adjacent said well and forming between them a groove of slightly greater width than a cigarette and having a curved bottom surface merging into the flat surface of the top, the combined length of said groove and extent of the flat surface in alignment therewith being not less than one-half the length of a cigarette.

3. In an ash-tray having an ash receptacle, the combination of a peripheral wall having a flat top surface portion for supporting a cigarette.

5 5. In an ash tray the combination of a substantially flat cigarette supporting surface, a well forming an ash receptacle, and extinguishing means comprising stationary spaced projections extending upward from said flat surface adjacent an edge of said well and forming between them a groove having a width slightly greater than the diameter of a cigarette and a depth of from one-half to one diameter of a cigarette, the bottom of said groove conforming approximately to the curved surface of a cigarette and having its lowermost portion in substantially the plane of said flat surface of the ash tray and forming a continuation of said surface.

10 4. In an ash-tray, an ash receptacle having a bottom and a peripheral wall, and cigarette supporting means comprising a flat supporting surface located above the bottom of the receptacle and within the outer periphery of said wall and a groove located between said flat surface and the inner periphery of said wall and adapted to support a cigarette in line contact with said surface and the bottom of said groove.

15 5. In combination with an ash receptacle, cigarette extinguishing means comprising a groove slightly wider than but closely fitting a cigarette without binding or gripping the cigarette and a flat cigarette supporting surface in the plane of the bottom of the said groove, of substantially greater width than said groove extending beyond said groove a distance not less than one-half the length of said groove, the combined length of the groove and supporting surface being not less than approximately one-half the length of a cigarette.

FELIX ALEXANDER JOSEPH.
